Primary Examiner — Jennifer Rivard*Assistant Examiner* — Jonathan E Fiencke(74) *Attorney, Agent, or Firm* — Fredrikson & Byron, P.A.(57) **CLAIM**

The ornamental design for an inline weir ring, as shown and described.

DESCRIPTION

FIG. 1 is a perspective view of an inline weir ring, showing my design;

FIG. 2 is a top view;

FIG. 3 is a front elevation view; and

FIG. 4 is a left-side elevation view;

FIG. 5 is a rear elevation view;

FIG. 6 is right side elevation view; and,

FIG. 7 is a bottom view.

The broken lines depict portions of the inline weir ring that form no part of the claimed design.
